Original application September 23, 1937, Serial
No. 165,326. Divided and this application May
16, 1944, Serial No. 535,819

16 Claims. (Cl. 290—38)

This invention relates to mechanism for controlling the operation of starting devices for internal combustion engines, particularly those of automotive vehicles.

Semi automatic devices for controlling the operation of the starting motor have been provided which have been so constructed that the starting motor is caused to operate in response to actuation of one of the control members which must be manipulated by the operator of the vehicle to control the operation of the engine as, for instance, the accelerator pedal, but which are also controlled by engine suction in such a way as to render the starting motor inoperative when the engine operates under its own power. Devices of this kind have been provided with a control switch operable in response to variations in engine suction which is so constructed as to be opened by suction as soon as the engine becomes self operative in order to break the circuit of the starting motor and thus render said motor inoperative.

In the past, difficulty has been encountered in designing a control switch of this character which would be held open at all times that the engine is operating under its own power, but which would not be opened by the suction thereon which is effective during the "cranking" of the engine by the starting motor in order to start the engine.

It is the principal object of the present invention to provide a starter control apparatus of the character referred to which employs a control switch provided with means to prevent any possible opening of the switch during operation of the engine by the starting motor but which will enable the switch to be automatically maintained open during operation of the engine under its own power.

This application is a division of applicants' copending application S. N. 165,326 filed Sept. 23, 1937.

Further objects and advantages of the present invention will be apparent from the following description, reference being had to the accompanying drawings wherein a preferred embodiment of the present invention is clearly shown.

In the drawings:

Fig. 1 is a side elevation of a dual carburetor in which the automatic mechanism for controlling the action of the choke valve and the engine starter is embodied.

Fig. 2 is a section along the line 2—2 of Fig. 1 with certain parts shown in elevation.

Fig. 3 is a horizontal section on the line 3—3 of Fig. 2 with certain parts shown in elevation.

Fig. 4 is a detailed sectional view on the line 4—4 of Fig. 3.

Fig. 5 is a diagrammatic section partly in elevation of the whole unit.

Fig. 6 is a detailed sectional view of the switch-operating mechanism showing the parts in the position occupied while the engine is being started.

Fig. 7 is a diagrammatic view of the circuit of the starter controlled system.

Referring primarily to Figs. 1 and 5, the reference numeral 10 indicates the carburetor in its entirety, such carburetor being provided with two intake passages 12 and 14, controlled by throttle valves 16 and 18 respectively, carried by a common shaft 20, while the number 22 indicates a fuel chamber of conventional type which partly surrounds the intake passages and supplies fuel thereto in any desirable way. The carburetor is of the down-draft type and is attached when in use to the intake manifold indicated at 24, while adjacent the manifold and case integral therewith is a chamber 26 through which exhaust gas passes. This may be the exhaust manifold itself, or may be a chamber connected for use combining what is known in the art as a "hot spot." This chamber supplies the heat that is utilized to heat the thermostat which regulates the choke valve in a manner hereinafter more fully described.

An operating connection for the throttle shaft of a conventional type is provided which is not shown and a connection 30 extends from the throttle shaft to an accelerator pump, this mechanism being no part of the present invention.

An unbalanced valve 32 is positioned in the air inlet 34 and the valve 32 is secured off center on a shaft 36 which is journaled for rotation in the walls of the air inlet 34 and is operable by the pressure of the incoming air. This valve obviously regulates the admission of air to the carburetor and the air flowing past such valve is mixed with fuel to form the mixture which is supplied by the passages 12 and 14 to the engine.

The shaft 36 to which the unbalanced valve is secured is adapted to be operated by mechanism which is controlled by a thermostat and engine suction as previously indicated, such mechanism being positioned within a housing 38 which is secured to the main housing of the carburetor by machine screws 40, or in any other suitable manner. To enable this mechanism to actuate the valve 32, the shaft 36 is connected in any suitable manner to one end of a flexible cable 42 which, as shown in the drawings, projects into

a recess 44 formed in one end of shaft 36 and is keyed thereto. The other end of the flexible cable projects into a similar recess 46 formed in the upper end of a shaft 48 which is journaled in a sleeve 50 received in the housing 38 as indicated in Fig. 1. The shaft 48 is suitably journaled for rotation and also journaled for rotation on the sleeve in a manner which does not constitute a part of this invention and is not shown herein, is a segmental gear 52, by means of which the suction operated mechanism is adapted to rotate the shaft 48, such suction operating mechanism operating through the medium of the thermostat as will be now described.

Depending from the segmental gear is a pin 54 which is suitably secured to the segmental gear and engages in a slot 56 formed in a bifurcated member 58, best shown in Fig. 5, which is secured by rivets, or in any other desirable way, to a thermostat 60 which is preferably in the form of a spiral coil that surrounds the lower end of the shaft 48 and has its lower end secured to the bottom of the shaft, the thermostat extending longitudinally of the shaft from the gear segment to the lower end of said shaft.

The means for securing the thermostat to the lower end of the shaft 48 is capable of adjustment in order to vary the force exerted by the thermostat on the shaft 48 for any given temperature when the temperature is low. This means includes a member or bracket 62 to which the lower end of the thermostat is riveted, as indicated in Fig. 2. A portion of the bracket is U-shaped in form, the lower arm of the U indicated by reference numeral 64 having an orifice therein through which the lower end of the shaft 48 passes, while the upper arm 66 of the U-shaped member is bifurcated and receives the shaft between the two forks thereof. The vertical portion 68 of the U-shaped member is provided with an orifice in which a set screw 70 is threaded so that the end of the screw engages the reduced portion 72 of the shaft 48 and may be tightened to secure the member 66 in any desired position with respect to the shaft.

The gear segment 52 is provided with teeth 74 which engage teeth 76 formed on the exterior surface of the piston member 78 received within a cylinder 80 formed within the housing 38 and the piston is normally adapted to be held in the position shown in Fig. 5 by a spring 82, which is received in the cylinder between the end thereof and the piston which is partially hollow to embrace the spring. The piston slides within the cylinder due to the suction of the engine and under the influence of other forces as will be more particularly set forth hereinafter, but when it is held in any given position by the spring 82, or by any other means, a change in temperature will cause expansion or contraction of the thermostat and if the piston be stationary at this time, the gear segment 52 is held stationary so that this expansion or contraction of the thermostat will cause the free end thereof to move and to so rotate the shaft 48 which, through the flexible connection 42 previously described, will move the valve toward open or closed position, expansion of the thermostat due to a rise in temperature causing the valve to open and contraction of the thermostat having the reverse effect and causing the valve to close.

The suction-operated piston hereinafter referred to, under normal conditions when the engine is not running, is held in position at the left of the cylinder in which it slides by the 75

spring 82. As soon as the engine starts to rotate when it is being turned by the starting motor during the cranking period and before the engine starts to run under its own power, suction is communicated to the cylinder in which the piston slides through the passage 84 which connects with a sump or chamber 86, indicated in dotted lines in Fig. 2, formed within the housing 38 and this in turn connects with a passage 88 also indicated in dotted lines in Fig. 2, which communicates with the carburetor intake passage just posterior to the throttle valves 16 and 18. Through this series of passages the manifold vacuum is communicated to the cylinder 80 to the right of the piston 78, as shown in Fig. 2, and any increase in such vacuum tends to move the piston to the right, while a decrease in vacuum tends to cause movement of the piston to the left.

20 The piston 78 is provided with a hollow extension 90 into which projects a rod 92 which extends through a closure member 94 secured in position at the end of the extension 90 in any suitable manner. The rod 92 has an enlarged head 96 secured thereto in any desirable manner, which slides within the extension 90 and has a loose fit therein, while at its opposite end such rod is screwed into or otherwise secured to a solid piston 98 which is slideable within a cylinder 100 formed in the housing 38 directly opposite the cylinder 80. The gear teeth 76 hereinbefore referred to, are formed on the outer surface of the extension 90 of the hollow piston 98.

25 The rod 92 has formed thereon integrally or secured thereto in any suitable manner, a flange 102 which projects from the rod and between which and the piston is received the upper end 104 of a spring arm 106, the lower end of which is coiled around a stud 108 secured in the wall 30 of the housing 38 and the other end of such spring is adapted to be engaged by one end 110 which projects from an arm 112 which is rotatable on the stud and when rotated increases the pressure of the spring, as later described.

30 Under normal circumstances, however, the spring 106 is held in the position shown in Fig. 5 by the arm 112 provided with an ear 114 which extends around the spring. The position of arm 112 is controlled by another spring 116 which is coiled around the stud 108 and has one end 118 engaging the carburetor housing while its other end 120 engages an end 122 projecting from an arm 124, which is connected by a yoke piece with arm 112, the two arms and yoke forming an integral structure rotatable on the stud 108. The pressure of the spring end 118 against the housing 38 reacts against end 122 through the other end 120 of the spring to hold the parts in the position shown, unless moved by means later described which will move the arm 112 in a clockwise direction, and will put tension on spring arm 104 to cause it to follow arm 112, as later described.

35 The cylinder 100 in which the piston 98 slides is provided with a resilient closure member 126 and the cylinder 100 and piston 98 constitute a dash pot which regulates the movement of the rod 92 and so regulates the speed of movement of the piston 78 to determine the time required for movement of the piston 78 and in this manner insures that the choke is not moved to its different positions too rapidly, the operation of these parts being more fully described later.

40 Attention is invited particularly to the fact that in the wall of the cylinder 100 there is provided

a tapered slot 128 which regulates the resistance of the above described dash pot to the motion of the parts controlled thereby so that the dash pot's resistance is less the further the piston 98 is moved to the right. In other words, the dash pot does not provide as great a resistance to movement of the parts as the choke valve approaches more open position and consequently the delay in its movement toward open position is reduced as the valve is opened progressively.

Cooperating with the mechanism just described to determine the position of rod 92 through the medium of the spring 104 is a cam 130, best shown in Fig. 2. This cam engages the roller 132 rotatably mounted on the end of the arm 124 and the cam is secured in any desirable manner to the shaft 20 on which the throttles 16 and 18 are mounted. The arrangement is such that as the throttles are moved toward their open positions the cam is rotated counterclockwise and through its engagement with the roller 132 the arm 124 is moved clockwise. The action of this arm and arm 112 is such as to move arm 112 out of the way of spring arm 104 so that spring arm 104 at its upper end can move to the right. At the same time the pressure of the spring arm 104 on the flange 102 is increased so that it will move piston 78 to the right as later described and the tension of the spring 116 is increased to restore the parts to normal when the cam is moved back to its original position. It will be obvious that a reverse motion of the throttle shaft would permit the roller 132 to move upwardly and cause the upper end of the spring 104 and other parts to be moved to the left by spring 116. At the same time the end of spring arm 104 through its engagement with piston 98, moves the rod 92 and piston 78 to the left, to effect a closing movement of the choke valve the movement of the piston 78 by rod 92 is brought about by engagement of flange 102 with the projecting portion 90 of the piston 16. The actual movements which the rod 92 makes under various operating conditions will be hereinafter more fully described.

It will be noted that the cam has a relatively steep portion 130a which is effective to move the arm 124 downwardly very considerably during the first part of the opening movement of the throttle and an almost concentric portion 130b which engages the roller 132 during the latter part of the throttle opening for reasons which will be later set forth. The construction is such that almost all the movement of arm 124 is effected during the first 40 degrees of throttle opening.

The gear segment 52 hereinbefore referred to and which is moved by the suction operated piston is limited in its movement in either direction depending upon the character of the mixture which is desired, so that the mixture which is formed by the carburetor can be varied in fuel ratio by means of this limiting of movement of the gear segment. In order that this movement of the gear segment may be variably limited for changes of temperature, variation of fuel volatility, or for any other reason that may be found desirable, the segment has two stops 140 and 142 (see Fig. 3) formed thereon which are adapted to engage with an eccentric member 144 carried by a pin 146 which extends through an opening in the housing 38 and is provided at its outer end with a knob 148 while between the knob and the wall of the housing is a spring washer 150 which presses against the wall of said housing when the nut is tight engaging orifices 152 formed in the

wall of the housing which act as detents to hold the eccentric member 144 in any desired position of adjustment. The knob may be turned and the eccentric member rotated so as to variably limit the movement of the two stops 140 and 142 as such stops are rotated upon lateral movement of the piston 78. By variably positioning the eccentric member the degree of pressure of the thermostat on the choke valve to hold the latter open or closed would be varied and this would vary the amount of air admitted for any given suction effect on the valve and so to this extent variably controls the mixture proportions for any setting of the eccentric member 144 and this setting of said eccentric member controls the richness of both cranking and running mixture.

It will be noted that the flexible cable 42 through which the movement of the automatic control unit is transmitted to the choke valve, is surrounded by a rubber housing 160 for protection and to prevent dirt and the like from getting on the flexible cable.

Heat is communicated to the thermostat to bring the thermostat up to or toward engine temperature through a heater tube 162. This lower end of the tube fits within a recess 164 formed in a boss 166 on the wall of the exhaust manifold 26 or on the hot spot as is found most desirable. The heater tube extends upwardly from the recess and surrounds a considerable portion of the thermostat forming an efficient means for conducting heat hereto as the engine temperature rises. The heater tube may be a single tube, or it may be surrounded with an outer tube 163 which fits outside of this heater tube and if used would serve a double purpose; first, to give the heater tube some more air and thus increase the efficiency and second, to protect the heater tube covering, dirt, water, etc. from entering the housing and from contact with the thermostat.

The preceding portion of this specification relates to the construction of the control unit which operates the choke valve to regulate the mixture proportions. According to the present invention there is embodied in this same control unit a switch which controls the action of the engine starter and the operation of which is controlled by the position of the throttle valve. This switch mechanism is positioned within a housing indicated in its entirety by the reference numeral 170 and which is adapted to be secured at the right hand end of the cylinder 80 as shown best in Fig. 2. The housing is provided with projecting ears 172 and 174 which are secured by machine screws 176 to the wall of the main unit housing 38 a gasket 178 being provided to form a tight joint between the main housing and the supplemental switch housing 170. The switch comprises two contacts 180 and 182, contact 180 being supported by a spring arm 184 which is bent at right angles as indicated in Fig. 5 and is secured to the housing 170 by rivets 186 but insulated therefrom by washers 188 of insulating material. The contact 182 is supported by a contact arm 186 of relatively rigid material which is bent at right angles and that portion of such arm most distant from the contact is separated from the housing 170 by a washer of insulating material 192 and is secured in the housing by rivets 194, or in any other desirable way. Binding posts 196 and 198 are provided, to which the wires leading from the starter control circuit to the switch formed by the contacts 180 and 182 were connected. This circuit will be more fully described hereinafter.

A spring 200 is received between the spring arm 184 and a screw 202 threaded in the housing 170. This spring tends to move the spring arm 184 in a direction to close the contacts 180 and 182 and by removal of the screw 202, springs of different strength or length can be substituted to adjust the pressure exerted on the contact carrying arm 184.

The operating means which control the opening and closing of the contacts 180 and 182 include connections from the throttle and connections operable by engine suction, the joint effect of which is to so control the contacts 180 and 182 that they cannot be closed except at such time as the engine is not running and after the throttle has been moved a predetermined distance toward its open position. Also the arrangement is such that the contacts cannot be opened during cranking of the engine, but will be held open at all times when the engine is operating no matter how low the engine speed.

In order that the throttle in its movement may control the action of these contacts, an arm 204 is secured to the throttle shaft by riveting such arm to the cam 130, or in any other suitable way. This arm 204 carries a projecting lip or lug 206 which is adapted to engage a rod 208 slidable in a bore in the wall of the main housing 38 and having a reduced end 210 which is designed to contact with the spring arm 184 to which the movable contact 180 is secured. The construction of the arm 204 and the length of the rod 208 are such that when the throttle is in fully closed position, as shown in Fig. 5, the rod occupies a position far enough to the right to hold the contact 180 out of engagement with the fixed contact 182 and in order for these contacts to close the throttle must move toward open position approximately 30 or more degrees.

The means which is controlled by engine suction for operating or controlling the switch comprising contacts 180 and 182 consists primarily in a cam 212 which is rotatably mounted on a stud 214 secured in the wall of the housing 170. Projecting from the cam is an arm 216 to which is pivotally connected a link 218, the other end of which is pivotally connected to an ear 220 formed on an angle-shaped member 222 which is secured by a rivet 224 to a diaphragm 226 the outer edge of which is secured between a flange 228 projecting from a cup-shaped metal shell 230 and a cooperating flange 232 formed on the housing 170. The edge of the shell 230 is crimped or spun around the flange 232 as indicated in Fig. 4 of the drawings to hold the diaphragm tightly between the flanges 228 and 232 and form a leak-proof joint. Washers 234 and 236 are provided on opposite sides of the diaphragm and are held in assembled position by the rivet 224 previously referred to. The washer 236 engages a spring 238 which is received between such washer and a shoulder 240 formed on the inside of the housing 170, said spring being adapted to hold the diaphragm in the position shown in Figs. 2 and 5, when there is no suction effective on such diaphragm or when the suction which is effective thereon is insufficient to overcome the pressure of the spring.

Suction is communicated to the interior of the housing 170 through the opening 242 which registers with the cylinder 80 when the housing 170 is assembled in position on the housing 38, as shown in Fig. 3 of the drawings.

It will be apparent from consideration of Fig. 5 that the spring arm 184, which carries contact 75

180, has projecting therefrom a pin 250 and when the cam 212 is in such position that the high surface thereon engages the pin 250, the contacts 180 and 182 can never engage. The cam is moved to this position by the action of the engine suction, as will be more fully explained later and when it is in such position, it is prevented from returning to the position occupied in Fig. 5 so long as the pin 250 remains on the cam surface 10 212 by reason of a projecting toe or latching member 252 which extends beyond the periphery of the cam and is adapted to engage the pin 250. As will be pointed out later, the cam assumes such position upon increased engine suction that 15 the high surface thereof engages the pin 250, and it cannot be returned to the position shown in Fig. 5, in which position the contacts 180 and 182 are permitted to close whenever the throttle is moved to such position as to allow such closing, until the throttle is moved to fully closed position which releases the pin 250 from the latch 252 and allows the cam 212 to be moved by the spring 238 to the position shown in Fig. 5 of the drawings.

25 It is obvious from inspection of Fig. 5 that the suction effect on the diaphragm 226 will move the link 218 upwardly to rotate the cam in a clockwise direction in order that the high surface may be brought opposite the pin 250. It is, however 30 necessary that such rotation should not take place during the cranking of the engine because such movement of the cam would separate the contacts 180 and 182 and if it took place during cranking, the engine might not be started. 35 Means are, therefore, provided to prevent the movement of the cam in the manner described until the engine suction is higher than is ever possible when operating it at cranking speed. The means for accomplishing this result comprises a spring detent which includes the spring 40 pressed ball 254 which engages an orifice or depression 256 in a sleeve 258 which is secured to the cam 212 and surrounds the stud 254. This sleeve is rotated with the cam and the spring held 45 ball exerts sufficient pressure against its seat to prevent any rotary motion of the sleeve until the vacuum becomes higher than is ever produced when the engine is rotated by the starting motor during cranking. In fact the spring which holds 50 the ball 254 in engagement with its seat in the sleeve 258 is of sufficient strength to prevent any rotary movement of the sleeve until a vacuum of 3 1/2 to 6 inches of mercury is reached. The operation of this control switch during various engine operating conditions will be more fully described hereinafter. In view of the provision of 55 this detent arrangement a very light diaphragm spring can be employed and so light a spring is used that a suction of 1/2" of mercury is enough to hold the switch open against the pressure of such spring. This prevents any possible closing 60 of the switches as long as the engine is running under any possible operating condition.

In Fig. 7 of the drawings there is provided a 65 diagrammatic view showing the control switch, the connections from the accelerator pedal to operate the throttle and the circuit of a preferred form of control device for the starting motor with which the control switch previously described is adapted to cooperate.

Referring to this figure, the starting motor is indicated at 260 and is provided with a shaft 262 on which slides a driving assembly through 70 which the motion of the starting motor shaft is communicated to the engine flywheel gear which

is indicated at 264. This assembly includes a sleeve 266 which is splined to the motor shaft 262 but slideable thereon, an overrunning clutch indicated in general by the reference numeral 268 and having one member thereof secured to the sleeve 266 and the other to a driving pinion 270 which is adapted to be moved into engagement with the engine flywheel gear 264. The whole assembly including the clutch, sleeve and pinion is adapted to be moved to the right to its gear meshing position by a lever 272 pivotally supported at 274 and the lower end of which engages a collar 276 slideable on the sleeve 266 and adapted to be held in the position shown by a coil spring 278 which is received between the collar and the clutch. When the lever 272 is moved in a counterclockwise direction it tends to move the entire driving assembly to the right sufficiently for the pinion 270 to be meshed with the gear 264 and if the teeth of the pinion and gear are so positioned that the pinion can slide into gear without abutment of the teeth, the assembly will be so moved. If, however, the pinion teeth abut those of the gear 264, the motion of the pinion to the right will be stopped but the lever will continue to move compressing the spring 278.

At the upper end the lever is connected to the armature 280 of a magnet which must be energized to move the lever 272 and at the opposite end the armature is provided with an enlarged head 282 which engages the movable contact 284 of the main starter switch which comprises in addition fixed contacts 286 and 288 and is normally held open by the pressure of a spring 290. When the motion of the lever 272 as described, is effective to move the movable contact 284 into engagement with contacts 286 and 288, the circuit of the starting motor is closed and the shaft 262 thereof is rotated. This rotation of the shaft will move the pinion 270 sufficiently to relieve the condition of tooth abutment above referred to and the spring 278 being collapsed and under pressure will immediately force the pinion into engagement with the engine gear 264.

The driving mechanism with the exception of the pinion shifting means, above described is not a portion of this invention in its detailed construction and is substantially what has been in public use for many years. While the magnet above referred to is not shown as of the same detailed construction as what has been in use for some years on the Buick and other automobiles, the identical magnet which has been so used can be used in place of that shown in the drawings, the only purpose of this disclosure being illustrative, and is purely diagrammatic, the details of the magnet being entirely unimportant so far as this invention is concerned.

The starting motor switch previously referred to is in circuit with a battery indicated at 292, the fixed contact 286 being connected by the lead 294 to the battery and is grounded through the connection 296. The other contact 288 of the starting motor switch is connected by the wire 298 to the commutator of the starting motor and is grounded through the connection 300. Obviously, when the contact 284 engages the contacts 286 and 288 current will pass from the battery through the lead 294, the switch comprising contacts above referred to, lead 298 to the starting motor and through the connection 300 to ground from which it will pass through connection 296 to the battery.

The closing of the above described switch is

effected as has previously been stated, by the action of a magnet having the armature 280. The magnet is provided with a winding designated by the number 310 which is grounded through the connection 312 and through the wire 314 is connected to the bolt 194 which secures the fixed contact 182 in position. The spring arm 184, as stated previously, is held in position by bolt 186 and to this bolt is connected the wire 316 leading from the fixed contact 320 of the ignition switch to the ignition system. The ignition switch is provided with a movable contact 322 which is connected by wire 324 to the wire 294 which has previously been described as extending to the battery. Obviously, when the contacts 180 and 182 are in engagement, current will flow from the battery through wire 294, wire 324, the ignition switch, wire 318 and wire 316 to the movable contact 180, thence through the fixed contact 182 when such switch is closed, to the bolt 194 and through the wire 314 to the winding 310 and thence to ground through the connection 312. The closing of the ignition switch at any time that the control switch comprising contacts 180 and 182 are closed, will, therefore, cause energization of the magnet and the motion of the armature 280 to the left with the result that the pinion 270 is placed in driving relation with the gear 264 and the main starting motor switch comprising contacts 284, 286 and 288 is closed to complete the circuit of the starting motor and cause the latter to operate. If either the ignition switch or the switch comprising contacts 180 and 182 be open, the circuit of the starting motor cannot be closed and the switch comprising contacts 180 and 182 is always maintained in an open condition during operation of the engine under its own power so that the starting motor can never be rendered operative while the engine is running.

The generator charging circuit comprises the wire 294 which leads to the battery and the wire 326 is connected therewith and extends to the generator 328 which is connected to ground through the connection 330. The usual cut-out relay is indicated at 332.

Operation

So far as the operation of that portion of the unit which controls the operation of the choke valve is concerned, the operation is not greatly different from the choke operating mechanism used on the 1937 Buick automobile, as the construction of the device herein disclosed is not greatly different from that one, the essentials of construction being the same and differing only in certain details.

If it be assumed that the engine is at rest and cold, with the throttle in closed position, the piston 78 is in its left hand position, as shown in Fig. 5, having been moved to that position by the cooperative action of the spring 82 and the thermostat 60, which upon contraction moves the piston to the left until its motion is stopped by engagement of the eccentric member 144 with its cooperating stop. With parts in this position, the choke valve is held closed by a force which varies inversely as the temperature. However, since the thermostat is held at one end by the spring 82 through the rack and segmental gear 76 and 74, the force exerted on such valve is no greater than the strength of spring 82 in its extended position.

When the starting motor circuit is closed and the starting motor is rendered operative for the

purpose of rotating the engine in order to start it, said engine rotation creates suction or a partial vacuum in the intake manifold which is communicated to the cylinder 80 to the right of piston 78. Due to the slow rotation of the engine at this time, however, the suction created is insufficient to overcome the forces holding the piston to the left and if the engine failed to start and the cranking period were prolonged, the engine would be flooded unless means were provided to prevent such action. Such a means is provided and is operable by the throttle to open the choke valve during cranking if this be found necessary.

To accomplish this result, the throttle operates the cam 130 to swing the arm 124 downwardly so as to move arm 112 out of the path of spring 104 to permit such spring to move to the right every time the throttle is opened. The spring 104 is stronger than spring 82, but exerts no force to move piston 78 to the right when the parts are in the position shown in Fig. 2, because of the action of spring 116. When the throttle opens, however, the pressure of the yoke on the opposite end of spring 104 builds up the pressure of such spring as arm 112 is moved out of the path thereof, so that the pressure exerted thereby on the piston is considerably greater than the pressure of spring 82. This action will move the rod 92, the piston 78, and in fact the whole assembly to the right as rapidly as the dash pot piston 98 will allow such action to take place. The retarding effect of the dash pot is, therefore, diminished as the piston is moved to the right by reason of the tapered slot. Obviously, if flooding occurs in the event of prolonged cranking, all that it is necessary to do is open the throttle which, through the medium of connections referred to, brings about a delayed opening movement of the choke valve. The throttle may then be closed and the cranking operation continued until the engine starts.

With the present construction, the throttle must be moved to a partly open position in order to start the engine for the reason that the switch contacts 180 and 182 cannot engage until the throttle reaches such position. There is, however, so much lost motion between the flange 102 and the extension 90 of piston 78 that the throttle can be moved to the position necessary for the switch to close without the accompanying movement of the rod causing any opening of the choke valve.

When the engine starts to run under its own power, the suction effective on the piston 78 greatly increases, as well as the flow of air through the carburetor which is effective on the unbalanced choke valve and these forces are enough to overcome the pressure exerted by spring 82 and the resistance of the dash pot to effect opening of the choke valve to a position determined by the suction and air flow. The action of the dash pot piston 98, however, retards the movement of the piston and thus prevents too rapid opening movement of the choke valve, or movement of the valve too far toward open position, in this way preventing the admission of sufficient air to lean the mixture to an undesirable extent when the engine is operating under its own power during the warm up period.

If, after the engine is operating under its own power, the throttle be opened to accelerate the engine, the spring arm 104 and the dash pot piston 98 cooperate to provide a mixture of proper proportions during this period, but it is not desirable that the mixture be enriched enough to

cause loading. Whenever the throttle is opened, the suction is reduced and the spring 82 tends to force the piston toward the left to effect a closing movement of the choke valve. This closing movement of the choke valve is controlled by the action of the dash pot and the spring arm 104.

With the structure disclosed, if it be assumed that the engine is operating at relatively low speed with but slightly open throttle, the piston 78 stands somewhat to the right and the flange 102 may be a considerable distance from the extension 90 of piston 78. When the throttle is opened the suction effective on the piston 78 immediately drops with the result that the spring 82 moves the piston toward the left to effect closing of the choke valve. This movement will be rapid until the extension 90 strikes the flange 102 when it will be stopped by the pressure of spring arm 104. Also after the extension 90 engages the flange 102, the assembly including the piston will be moved back toward the right as the throttle continues toward open position so that the closing movement of the choke valve is only temporary. Thus the first action occurring upon opening movement of the throttle is a closing of the choke valve, followed by a second action which is an opening of the valve due to the opening movement of the throttle which rotates cam 130, increasing the force of spring arm 104 and moving the piston 78 toward the right against the pressure of spring 82, to again move the choke valve toward open position. This action permits the choke valve to assume a position where it is in a condition of balance, as determined by the several springs operating thereon, the force of the thermostat and engine suction and prevents too great enrichment of the mixture upon acceleration.

It will also be understood that if the throttle be opened for acceleration after it has reached a position where the surface 130b of arm 130 is engaged by its cooperating roller there will be substantially no temporary closing of the choke for acceleration purposes because the flange 102 will, under such conditions, have been moved into engagement with extension 90 of piston 78 and, therefore, a drop in suction following the opening of the throttle will not be effective to move the piston to the left. Moreover, the further movement of the throttle toward open position does not cause any considerable movement of the piston to the right, because of the nearly concentric shape 130b of the cam 130. The above described action is desirable because after a predetermined throttle opening is reached, temporary closing of the choke valve for acceleration purposes is substantially unnecessary.

It will be understood that the rate of movement of the piston 78 toward the right, and consequently the rate of movement of the choke toward open position will be determined by the movement of the dash pot piston 98 toward the right, and it will also be apparent that the retarding effect of such dash pot piston will be progressively reduced as said piston moves toward the right. It is not necessary to retard the opening movement of the choke to as great a degree when said valve approaches its open position as when said valve is more nearly closed. This control of the retarding effect of the dash pot is brought about by the tapered slot previously described, which is formed in the wall of the dash pot cylinder 100.

It will also be apparent that the dash pot con-

trols the movement to the left of piston 18 when the throttle is closed from an open position as the return spring can return the parts no more rapidly than the dash pot permits.

Coming now to the operation of the control switch by means of which the action of the starting motor is automatically regulated, it is obvious from consideration of the circuit diagram in Fig. 7, that the ignition switch and the switch comprising contacts 180 and 182 must be closed and whenever the ignition switch or the control switch is open, the starting motor circuit is broken. When the engine is at rest, with the throttle closed, the ignition switch is open and also the control is open because the closing of the throttle through the medium of the arm extending from cam 130 moves the rod operated thereby so far to the right that it pushes the spring arm 184 so far to the right that the control switch is open. Under these conditions the suction operated latch is in the position shown in Fig. 5.

To start the engine, assuming the throttle is closed and the ignition turned off, it is necessary to close the ignition switch since this switch is in series in the starter control circuit and also to move the throttle sufficiently toward open position to permit the rod 208 to move to the left enough to cause the control switch embodying contacts 180 and 182 to close. This movement of the throttle is approximately 35° or thereabouts toward open position, which has been found desirable to provide the desired quantity of mixture for starting purposes. The closing of the ignition switch and the closing of the control switch as described, complete the control circuit with the result that the magnet is operated to shift the driving pinion into engagement with flywheel gear and at the same time close the main starting motor circuit, as previously described. The starter motor becomes operative then and will start the engine. As earlier pointed out, if the engine does not start promptly and the cranking period is prolonged without results, the operator should open the throttle for the purpose of relieving flooding, as previously described.

When the engine starts to run under its own power, the action of the engine suction is such as to move the high surface of the control cam into engagement with the pin on spring arm 184 to open the control switch and break the starter circuit when the starter will become inoperative. As long as the engine suction remains relatively high, the control cam will be held in such position that the high surface is opposite the pin on the spring arm 184 which is adapted to engage such cam surface and will hold the switch open. If, however, the engine is operating under heavy load with wide open throttle, the suction would drop and if means were not provided to prevent such action, it might be possible to close the starting motor circuit and cause serious damage to the starting system. This action is prevented by means of a latch member which is carried by the cam and which engages the pin on the spring arm 184 to prevent a return of the control cam to its original position until the throttle has been allowed to close so as to move the pin out of the path of the latch member. Of course, if the throttle is closed, the suction immediately becomes high and the cam will not be permitted to move to a position where the control switch can be closed because of the high suction. If the throttle is again opened so that the suction drops, the latch will become again effective.

The spring detent which controls the operation of the cam and the latch member is an important feature of this invention and makes it substantially impossible for the control switch to be closed under any operating conditions which can be met. It is obviously necessary that a device of this character must be constructed so that the control switch cannot be opened during engine cranking or else the starter circuit would be broken and the engine would not be started. Due to the fact that the throttle is generally in only a partly open position during cranking, the suction may be higher when the engine is being turned by the starting motor for the purpose of starting it than when it is operating under its own power with a relatively open throttle and heavy load. It has been found necessary to provide a device which will not open during cranking under a suction of from 3 1/2 inches of mercury, but will hold open during operation at a suction much lower than that. The spring detent hereinbefore described, produces these results and because of the engagement of the spring-held ball with the cam member, the cam cannot be moved by engine suction until a vacuum of some 3 1/2 inches of mercury is reached, but after the ball is disengaged from the recess in which it normally seats in the cam chamber, the cam will be held by a suction of as little as a half an inch of mercury in its position where it will hold the switch open. This feature of operation is of considerable importance because even when operating under a part throttle condition where the vacuum would normally be high enough to hold the control switch open, under such conditions the throttle might be in a position that the rod 208 does not hold the switch open, the operator might increase the load by stepping on the brake for some purpose, in which event the engine would slow down and the suction drop off to a point less than the cranking suction. However, with the construction shown there is always under all conditions sufficient vacuum to hold the control switch open.

While the embodiment of the present invention as herein disclosed, constitutes a preferred form, it is to be understood that other forms might be adopted, all coming within the scope of the claims which follow.

What is claimed is as follows:

1. In a starting apparatus for internal combustion engines having a starting motor, a current source, a circuit for connecting said motor and current source, a control switch for controlling said circuit, means operable by engine suction for preventing the closing of said switch while the engine is self-operative, resilient means engaging said suction operated means when the switch is closed and exerting a force to prevent operation of said suction operated means, which is appreciably greater than the force exerted on said means by engine suction during rotation of the engine by the starting motor but less than the force exerted by engine suction when the engine becomes self-operative.
2. In a starting apparatus for internal combustion engines having a current source, a starting motor operable by current from said source and a circuit for connecting said starting motor with the current source, a switch for controlling said circuit, means for operating said switch, a control member movable to two positions in one of which it prevents closing of the switch and in the other of which it permits said switch to be closed to cause operation of the starting motor,

means operable by the engine when it becomes self-operative to move said control member to a position where it prevents closing of the switch, and means engaging said control member for preventing such movement of said control member while the engine is being operated by the starting motor, said last named means being ineffective to prevent such movement of said control member whenever the engine begins to operate under its own power.

3. In a starting apparatus for internal combustion engines having a current source, a starting motor operable by current from said source and a circuit for connecting said starting motor with the current source, a switch for controlling said circuit, means for operating said switch, a control member movable to two positions in one of which it prevents closing of the switch and in the other of which it permits said switch to be closed to cause operation of the starting motor, means operable by engine suction when the engine begins to run under its own power to move said control member to a position where it prevents closing of the switch, and means engaging said control member for preventing such movement of the control member while the engine is being operated by the starting motor, said engaging means being ineffective to prevent movement of the control member whenever the engine becomes self-operative.

4. In a starting apparatus for internal combustion engines having a current source, a starting motor operable by current from said source and a circuit for connecting the starting motor with said current source, a switch for controlling said circuit and provided with a plurality of contact members, a control member movable by engine suction to a position to prevent closing of the switch when the engine becomes self-operative, means engaging said control member to hold it in position to prevent closing of the switch as long as the engine is self-operative and manually operable means effective when moved in one direction to disengage said last named means from the control member to permit the latter to return to its normal inoperative position when the engine is not running in order to permit closing of the switch and effective when moved in the other direction to cause said switch to be closed in order to render the starting motor operative.

5. In a starting apparatus for internal combustion engines having a current source, a starting motor operable by current from said source and a circuit for connecting the starting motor with said current source, a switch for controlling said circuit and provided with a plurality of contact members, a control member movable by engine suction to a position to prevent closing of the switch when the engine becomes self-operative, a latch for engaging the surface of the control member when said member has been moved by engine suction to the position it occupies when the switch is held open, to maintain said control member in such position as long as the engine is self-operative, and manual means for disengaging the latch from the control member to permit the control member to return to its normal inoperative position when the engine becomes inoperative, so that the switch may be closed to start said engine.

6. In a starting apparatus for internal combustion engines having a current source, a starting motor operable by current from said source and a circuit for connecting the starting motor

with said current source, a switch for controlling said circuit and provided with a plurality of contact members, a control member movable by engine suction and having a cam formed thereon

5 with one abrupt face, said control member being moved to a position where the cam prevents closing of the switch, and a latch member for engaging the abrupt face of the cam to hold the control member in position to prevent closing 10 of the switch as long as the engine is self-operative, and manual means for effecting release of the cam from the latch to permit return of the control member to normal position.

7. In a starting apparatus for internal combustion engines having a current source, a starting motor operable by current from said source and a circuit for connecting the starting motor with said current source, a switch for controlling said circuit and provided with a plurality of contact members, a control member movable by engine suction to a position to prevent closing of the switch when the engine becomes self-operative, means engaging said control member and effective to prevent movement of said control member by suction during operation of the engine 20 by the starting motor, but ineffective to prevent movement of said control member by suction when the engine becomes self-operative, and a second means effective to hold the control member in the position to which it is moved by engine suction as long as the engine is self-operative, to prevent any possible closing of the starting motor circuit while the engine is running under its own power.

8. In a starting apparatus for internal combustion engines having a current source, a starting motor operable by current from said source and a circuit for connecting the starting motor with said current source, a switch for controlling said circuit and provided with a plurality of contact members, a control member movable by engine suction to a position to prevent closing of the switch when the engine becomes self-operative, means engaging said control member and effective to prevent movement of said control member by suction during operation of the engine by the starting motor, but ineffective to prevent movement of said control member by suction when the engine becomes self-operative, and a latch adapted to directly engage the control member to hold said member in the position to which it is moved by engine suction as long as the engine is self-operative to prevent any possible closing of the starting motor circuit while the engine is running under its own power.

9. In a starting apparatus for internal combustion engines having a current source, a starting motor operable by current from said source and a circuit for connecting the starting motor with said current source, a switch for controlling said circuit and provided with a plurality of contact members, a control member movable by engine suction to a position to prevent closing of the switch when the engine becomes self-operative, means engaging said control member and effective to prevent movement of said control member by suction during operation of the engine by the starting motor, but ineffective to prevent movement of said control member by suction when the engine becomes self-operative, a second means effective to hold the control member in the position to which it is moved by engine suction as long as the engine is self-operative, to prevent any possible closing of the starting motor circuit while the engine is running

under its own power, and manual means for disabling said last named means so as to permit the control member to return to the position from which it is moved by engine suction.

10. In a starting apparatus for internal combustion engines having a current source, a starting motor operable by current from said source and a circuit for connecting the starting motor with said current source, a switch for controlling said circuit and provided with a plurality of contact members, a control member movable by engine suction to a position to prevent closing of the switch when the engine becomes self-operative, means engaging said control member and effective to prevent movement of said control member by suction during operation of the engine by the starting motor, but ineffective to prevent movement of said control member by suction when the engine becomes self-operative, a latch adapted to directly engage the control member to hold said member in the position to which it is moved by engine suction as long as the engine is self-operative to prevent any possible closing of the starting motor circuit while the engine is running under its own power, and manual means for disengaging the latch so as to permit the control member to return to the position from which it is moved by engine suction.

11. In a starting apparatus for internal combustion engines having a current source, a starting motor operable by current from said source and a circuit for connecting the starting motor with said current source, a switch for controlling said circuit and provided with fixed and movable contact members, a control member engaging said movable contact and movable by engine suction to a position to prevent movement of the contact to a position to close the switch when the engine becomes self-operative, and means whereby the movable contact is effective to hold the control member in position to prevent closing of the switch as long as the engine is self-operative.

12. In a starting apparatus for internal combustion engines having a current source, a starting motor operable by current from said source and a circuit for connecting the starting motor with said current source, a switch for controlling said circuit and provided with fixed and movable contact members, a control member engaging said movable contact and movable by engine suction to a position to prevent movement of the contact to a position to close the switch when the engine becomes self-operative, means whereby the movable contact is effective to hold the control member in position to prevent closing of the switch as long as the engine is self-operative and manual means effective to release the control member from said movable contact in order to permit said control member to return to the position from which it is moved by engine suction.

13. In a starting apparatus for internal combustion engines having a current source, a starting motor operable by current from said source and a circuit for connecting the starting motor with said current source, a switch for controlling said circuit and provided with fixed and movable contact members, a control member movable by engine suction to a position to prevent closing of the switch when the engine becomes self-operative, means engaging said control member

and effective to prevent movement thereof by suction during operation of the engine by the starting motor and means whereby the movable contact is effective to hold the control member in position to prevent closing of the switch as long as the engine is self-operative.

14. In a starting apparatus for internal combustion engines having a current source, a starting motor operable by current from said source and a circuit for connecting the starting motor with said current source, a switch for controlling said circuit and provided with fixed and movable contact members, a control member movable by engine suction to a position to prevent closing of the switch when the engine becomes self-operative, means engaging said control member and effective to prevent movement thereof by suction during operation of the engine by the starting motor, means whereby the movable contact is effective to hold the control member in position to prevent closing of the switch as long as the engine is self-operative, and manual means for rendering the movable contact ineffective to hold the control member in position to prevent closing of the switch in order to permit the control member to return to the position from which it was moved by engine suction.

15. In a starting apparatus for internal combustion engines having a current source, a starting motor operable by current from said source and a circuit for connecting the starting motor with said current source, a switch for controlling said circuit and provided with fixed and movable contact members, a control member engaging said movable contact and movable by engine suction to a position to prevent movement of the movable contact to a position to close the switch when the engine becomes self-operative, said control member having a surface thereon adapted to be engaged by said movable contact when the control member is moved to a position to hold the switch open so as to hold the control member in such position, and another means engaging the control member and effective to prevent movement of said control member when the engine is operated by the starting motor.

16. In a starting apparatus for internal combustion engines having a current source, a starting motor operable by current from said source and a circuit for connecting the starting motor with said current source, a switch for controlling said circuit and provided with fixed and movable contact members, a control member engaging said movable contact and movable by engine suction to a position to prevent movement of the movable contact to a position to close the switch when the engine becomes self-operative, said control member having a surface thereon adapted to be engaged by said movable contact when the control member is moved to a position to hold the switch open so as to hold the control member in such position, another means engaging the control member and effective to prevent movement of said control member when the engine is operated by the starting motor, and manual means operable to disengage the movable contact from said surface so as to permit the control member to return to the position from which it is moved by engine suction.
